MULTI-PURPOSE ELECTRICIAN'S TOOL

Ted Neff, La Habra, Calif., assignor to Hunter Industries,
Santa Fe Springs, Calif., a corporation of California

Filed July 31, 1969, Ser. No. 18,498

Term of patent 14 years

Int. Cl. D8—02

U.S. Cl. D8—58

FIG. 1 is a perspective view, open position, of a multi-purpose electrician's tool showing my new design;

FIG. 2 is a side elevational view thereof, closed position;

FIG. 3 is a top plan view;

FIG. 4 is a bottom plan view;

FIG. 5 is a front elevational view; and

FIG. 6 is a rear elevational view.

I claim:

The ornamental design for a multi-purpose electrician's tool, as shown and described.
